UNITED STATES PATENT OFFICE.

BENJAMIN C. WALLACE, OF STOCKTON, CALIFORNIA.

CASKET-CANOPY.

1,020,169.

Specification of Letters Patent. Patented Mar. 12, 1912.

Application filed March 2, 1910. Serial No. 546,782.

To all whom it may concern:

Be it known that I, BENJAMIN C. WALLACE, a citizen of the United States, residing at Stockton, in the county of San Joaquin, 5 State of California, have invented certain new and useful Improvements in Casket-Canopies; and I do declare the following to be a full, clear, and exact description of the same, such as will enable others skilled 10 in the art to which it appertains to make and use the same, reference being had to the accompanying drawings, and to the characters of reference marked thereon, which form a part of this application.

15 This invention relates to improvements in funeral paraphernalia and particularly to canopies for the caskets, the object of the invention being to produce a canopy to cover caskets which will be artistic and pretty and 20 at the same time collapsible and capable of being unfolded and put up or taken down and folded in a few seconds, this being the advantage gained over the commonly used present day canopies which are complicated 25 and of many parts and require from fifteen minutes upward of time to set up or take down.

A further object of the present invention is to produce a simple and inexpensive device 30 and yet one which will be exceedingly effective for the purposes for which it is designed.

These objects, I accomplish by means of such structure and relative arrangement of 35 parts as will fully appear by a perusal of the following specification and claim.

In the drawings similar characters of reference indicate corresponding parts in the several views.

40 Figure 1 is an outline view of the upper portion of the canopy as it appears in open position. Fig. 2 is a perspective view of the folding skeleton or frame of the canopy as it appears in open position. Fig. 3 is a rear elevation of the same in folded position. Fig. 4 is a sectional view taken on a line $x-x$ of Fig. 2. Fig. 5 is a fragmentary view of a frame 3 showing a wrapping tape thereon. Fig. 6 is a fragmentary view of a hanging ring showing the method of securing supporting tapes thereon.

50 Referring now more particularly to the characters of reference on the drawings 1

and 2 designate the main bars or beams of 55 the frames which are hinged together in parallel relation and each has a projecting wire frame 3 having their ends bent as at 4 and fitting into grooves 5 in the members 1 and 2 and secured there by staples or other 60 fastening means 6. Each of the frames 3 are wound or bound with a soft tape 7 to prevent frictional wear and to permit the drapery silk 8 to be sewed or secured thereto. 65

Secured on each corner of each frame 3 as at 9 and projecting through a ring 10 to the opposite corner of the other frame 3 is a supporting tape 11 while 12 is a supporting tape secured to both frames 1 and 2 at 70 each end and passing also through the ring 10, such tape 12 crossing each other and forming an intervening free space at 13 to permit the members 1 and 2 to fold; and the lengths also of the tapes 11 and 12 are 75 such as to permit the members 3 to fold to a completed folded position as shown in Fig. 3.

All the members 11 and 12 are bound firmly together just beneath the ring 10 by 80 a cord 14 thus holding the ring 10 in a rigid fixed position, hence to unfold the canopy the operator grasps said ring and the skeleton is pulled and opens into open position whereas to fold it again the ring 10 is left 85 loose and the frame folded to closed position.

The drapery 8 is draped over the skeleton or frame in any desired artistic manner.

From the foregoing description it will be 90 readily seen that I have produced such a device as substantially fulfills the objects of the invention as set forth herein.

While this specification sets forth in detail the present and preferred construction 95 of the device, still in practice such deviations from such detail may be resorted to as do not form a departure from the spirit of the invention.

Having thus described my invention what 100 I claim as new and useful and desire to secure by Letters Patent is:

A casket canopy comprising two members hinged together in parallel relation, a projecting rectangular frame on each of said 105 members, a tape extending from each end of each said parallel members to the opposite end of its adjacent member, a tape ex-

tending from each outer corner of each of said rectangular frames to the opposite corner of its adjacent frame, all of said tapes passing through a common ring, means binding all of said tapes together just below said ring, and a canopy draped over said tapes and frames.

In testimony whereof I affix my signature in presence of two witnesses.

BENJAMIN C. WALLACE.
